Harry Smith

UNITED STATES PATENT OFFICE.

ADAM HASKELL, OF LOOKOUT MOUNTAIN, TENNESSEE.

DESIGN FOR A PORTABLE SERVING-TABLE.

55,945.

Specification for Design.

Patented Aug. 3, 1920.

Application filed April 27, 1920. Serial No. 377,115. Term of patent 14 years.

To all whom it may concern:

Be it known that I, ADAM HASKELL, a citizen of the United States, residing at Lookout Mountain, Tennessee, have invented a new, original, and ornamental Design for a Portable Serving-Table, of which the following is a specification.

In the accompanying drawing—

Fig. 2 is an end view of the same.

I claim:

The ornamental design for a portable serving table, as shown.

ADAM HASKELL.
